HAIR DRYER

Lawrence I. Freedman, Wilmington, Del., John W. Tome, Zebleys Corner, Pa., and Seymour Rappoport, Rumson, N.J., assignors, by mesne assignments, to Ronson Corporation, Woodbridge, N.J., a corporation of New Jersey

Filed May 3, 1960, Ser. No. 26,522
10 Claims. (Cl. 219—39)

This invention relates to a portable hair dryer, and it more particularly relates to a portable hair dryer which discharges its stream of air either directly or through hose-connected attachments.

It has been found advantageous to use portable hair dryers in two different ways. In one mode of operation the hair dryer is held in the hand of the user, and the stream of discharged air is played directly upon the hair. This ties up the use of one hand and requires constant attention during the drying operation, and various types of hoods have been connected with these portable dryers by means of flexible hoses to permit a person to perform other functions while the hair is being dried. Furthermore, other attachments have been provided for these hoses such as combs. This has created a support problem for these portable dryers because units that are stable when resting upon a surface are generally inconvenient to hold in the hand and vice versa.

An object of this invention is to provide a structure for a portable hair dryer which facilitates both its direct use and its use in conjunction with hose-connected attachments;

Another object is to provide such a dryer which is stably supported both in the hand or resting upon a surface; and

A further object is to provide means for conveniently connecting a hose to such a dryer.

In accordance with this invention a lever element is rotatably connected to the casing for supporting it in its operative positions. This lever element is rotatable to positions adjacent and removed from the casing, and it has one side which is constructed and arranged to provide a supporting base for resting the casing upon a surface when the lever element is rotated into a position where it lies adjacent the casing. This provides a stable support with a low center of gravity for the dryer when a flexible hose and attachments are connected to it.

An end of this lever element is also constructed and arranged as a handle to permit the dryer to be conveniently held in the hand when the lever element is rotated to a position removed from the casing. This facilitates the manipulation of a unit by a means which can securely support it when it is resting upon a surface.

A highly convenient means for connecting a flexible hose to such a dryer is provided by shaping the outlet of the casing in the form of an expanded bellmouth. Coupling elements are disposed within a narrow portion of this bellmouth, and a coupling adapter in the end of the hose engages these coupling elements. This adapter includes apertures disposed within a larger portion of the bellmouth which provide a safety exhaust for heated air should the discharge end of the hose become blocked for any reason. A highly convenient form of coupling adapter for a flexible hose incorporating a helical spring of resilient wire is provided by a tubular sleeve of substantially rigid material bearing a helical ridge which is engaged within the helical wire of the hose.

Novel features and advantages of the present invention will become apparent to one skilled in the art from a reading of the following description in conjunction with

the accompanying drawings wherein similar reference characters refer to similar parts and in which:

FIG. 1 is a side view in elevation of one embodiment of this invention in the condition in which it is held in the hand;

FIG. 2 is a side view in elevation in cross-section of the embodiment shown in FIG. 1 in the condition in which it rests upon a surface;

FIG. 3 is a side view of the coupling adapter shown in FIG. 2;

FIG. 4 is an end view of the coupling adapter shown in FIG. 3;

FIG. 5 is a rear view of the embodiment shown in FIG. 1;

FIG. 6 is a front view of the embodiment shown in FIG. 1;

FIG. 7 is a sectional view taken through FIG. 2 along the line 7—7; and

FIG. 8 is a sectional view taken through FIG. 2 along the line 8—8.

In FIG. 1 is shown a portable hair dryer 10 including a casing 12 incorporating an upper shell 14 and a lower shell 16. A blower 54 and a heater unit 56 (shown in FIG. 2) are mounted within casing 10, and they are controlled by switch knob 18 mounted upon an upper portion of casing 12. Air inlet openings 20 are provided in the rear of casing 12, and an air outlet opening 22 is provided in the front of casing 12. A lever element 24 is rotatably attached to a lower portion of casing 12, by a pivot means 26 which includes a pivot nut and screw 28 supported within fin 30 extending from the lower portion of casing 12. Fin 30 is inserted within a longitudinal recess 31 in an upper portion of lever 24 as shown in FIG. 5.

In FIG. 1 lever element 24 is shown in a position removed from casing 12 to facilitate holding dryer 10 in the hand. The end 34 of lever element 24 is therefore shaped as a handle as better illustrated in FIG. 5 to permit it to be grasped in the hand while the fingers may rest comfortably against arms 36 which extend laterally from lever element 24. The front end 37 of lever element 24 incorporates a wall 38 which engages the slanted front surface 40 of fin 30 to provide a stop for holding lever element 24 in the manipulating position removed from casing 12 as shown in FIG. 1. An elongated longitudinal projection 42 extends from a lower surface of lower casing half 16. Projection 42, as shown in FIG. 5, has an open rear end 44 through which an electric conduit 46 passes into lower casing half 16. Projection 42 nests within longitudinal recess 48 in the handle portion 34 of lever element 24 when the handle is rotated or folded against casing 12 as shown in FIG. 2.

In FIG. 2 is shown the condition of dryer 10 when lever element 24 is rotated adjacent casing 12 to provide a base for supporting dryer 10 upon a surface. This condition is utilized both for storing dryer 10 and for operating it in conjunction with attachments (not shown) connected to it by a hose assembly 50. This supporting function of lever element 24 is facilitated by supporting feet 52 extending from longitudinally and laterally displaced portions of lever element 24 such as front end 37 rear or handle end 34, and arms 36. These feet are for example rubber inserts 52 attached to lever element 24 by insertion into suitable recesses formed within it. Lever element 24 as well as both halves 14 and 16 of casing 12 are conveniently fabricated from a moldable plastic such as polystyrene of a type which resists impact.

In FIG. 2 are illustrated blower unit 54, heating unit 56 and switch assembly 58 of which operating knob 18 is mounted outside of casing 12. Impeller 60 is mounted upon shaft 62 of electric motor 63, and it is, for example, conveniently molded of a plastic such as nylon.

Electric conduit or cord 46 is confined within groove

64 whose open end 44 is shown in FIG. 5 by a T-shaped element 66 also shown in FIGS. 7 and 8. The arms 68 of T-shaped element 66 are secured to bosses 70 extending from casing half 16, and separate wires 72 extend laterally from cord 46 between the downwardly bent front flange 74 of T 66, front surfaces of bosses 70 and the adjacent upper surface of the casing interior. This provides a convenient means for confining and anchoring the electrical wiring within casing half 16 and introducing it into the casing. T 66 is conveniently fabricated of a moldable plastic material, and its rear end 76 is visible in FIG. 5 at the upper portion of apertures 44.

Discharge aperture 22 at the front end of casing 12 is formed in the shape of an expanding bellmouth, and it incorporates coupling elements 78 of the bayonet type for locking adapter 80 of hose assembly 50 within the discharge end of dryer 10. Apertures 82 are provided in a portion of adapter 80 outside of hose 84 which permits a minimum flow of air from dryer 10 even if the other end of hose 84 should become blocked for any reason. This prevents the unit from overheating and blowing a fuse if the outlet from hose 84 should become blocked. This safety flow of air is facilitated by the disposition of aperture 82 within expanded bellmouth 32 of dryer 10.

Adapter 80, made of a substantially rigid plastic, is secured within the end of hose 84 by the engagement of the single turn of the helical ridge 86 on a surface within resilient helical wire 88 of hose 84. Hose 84 is made of a plastic coated resilient wire 88 inserted within a tubular plastic sheath 90, and the configuration of helical ridge 86 substantially corresponds to the free form of helical wire 88 within its sheath. Helical ridge 86 fortuitously firmly locks adapter 80 within the end of hose 84 even though it freely screws into it, and a permanent connection is thereby provided in an extremely convenient and economical fashion. This connection is unexpectedly permanent because the diameter of the helical wire will reduce if one attempts to unscrew it, thereby increasing its grip upon the outer surface of adapter 80 which effectively resists an unscrewing action. The circular ridge 92 on adapter 80 between locking projections 81 and apertures 82 provides a convenient means of gripping and manipulating the end of the hose into which it is inserted. The outlet 22 of dryer 10 is shielded by an apertured plate 94 shown in FIG. 6. This plate, as indicated in FIG. 2, is locked within suitable recesses formed within the upper and lower halves of the casing 14 and 16.

Operation

When dryer 10 is held in the hand to dry the hair, lever element 24 is rotated away from casing 10 to the position shown in FIG. 1 to make handle 34 accessible. Handle portion 34 is then grasped in the hand of the operator for which access is provided by rotation of this handle away from the casing, and arms 36 provide a convenient resting point for some of the fingers of the hand. The disposition of the center of gravity of the dryer somewhere over the hand to the rear of the connection of the lever with the casing facilitates its retention in a balanced fashion. Furthermore, lower wall 38 of forward extension 37 contacts the forward edge 40 of fin 30 of casing 12 to provide a stop for lever element 24 in the handle-providing position shown in FIG. 1.

When it is desired to store the unit or when it is to be used in conjunction with attachment to hose assembly 84, lever element 24 is rotated adjacent casing 12 as shown in FIG. 2, and the unit is placed upon a reasonably flat surface. The disposition of the center of gravity above the central portion of the long base that lever element 24 provides and the lateral extensions of arms 36 provide an extremely stable support which is facilitated by the low center of gravity afforded by the folding of lever element 24 adjacent the casing. Even if hose 84

is twisted and turned, dryer 10 will therefore not be tipped over. This stability is enhanced by the forward extension 37 of lever arm 24 which prevents tipping over of the front end of the unit.

5 A highly convenient and attractive mode of introducing an electric cord 46 into casing 12 is provided by longitudinal projection 42, and the anchoring and guidance of cord 46 and its incorporated wires 72 are facilitated by T-shaped bracket 66. Furthermore, the unit is prevented from overheating even if a blockage of the discharge hose assembly 84 occurs by the flow of air through apertures 82 formed in the coupling adapter 80. This coupling adapter 80 is conveniently secured to a flexible hose of the type described by engagement of its helical ridge 86 within helical resilient wire 88 of hose 84.

10 What is claimed is:

1. A structure for a portable hair dryer comprising a casing, blower and heating units mounted within said casing for propelling a stream of heated air from it, inlet and outlet openings in said casing for introducing air into and discharging it from said casing, a lever means including a lever element and pivot means having an axis of rotation, said pivot means rotatably attaching said lever element to said casing for supporting it in its operative positions, said lever element being rotatable to operative positions adjacent and removed from said casing, said axis of said pivot means being somewhat removed from the center of gravity of said casing and the units mounted within it for disposing said center of gravity over a central portion of said lever element thereby balancing said dryer over said lever element in both of its operative positions, the portion of said lever means disposed adjacent said axis being laterally extended to provide a base for supporting said dryer in a stable operative position upon a surface when said lever element is in said position adjacent said casing, a portion of said lever element remote from said pivot means being relatively elongated and compact in cross section whereby it is constructed and arranged as a handle to permit said dryer to be securely held in the hand when said lever element is in said position removed from said casing, and said laterally extending portions of said lever means providing a rest surface for the fingers of a hand grasping said handle.

2. A structure as set forth in claim 1 wherein said casing is an elongated envelope with said inlet opening disposed at its rear end and its outlet opening disposed at its front end, and said pivot means being disposed slightly forward of the center of gravity of said casing.

3. A structure as set forth in claim 2 wherein a portion of said lever element extends a distance in front of said pivot means for preventing said casing from being tipped forward when it is supported upon a surface.

4. A structure for a portable hair dryer comprising a casing, blower and heating units mounted within said casing for propelling a stream of heated air from it, inlet and outlet openings in said casing for introducing air into and discharging it from said casing, a lever element, pivot means rotatably attaching said lever element to said casing for supporting it in its operative positions, said lever element being rotatable to positions adjacent and removed from said casing, a portion of said lever element being laterally extended to provide a base for supporting said dryer upon a surface when said lever element is in said position adjacent said casing, an end of said lever being relatively elongated and compact in cross section whereby it is constructed and arranged as a handle to permit said dryer to be held in the hand when said lever element is in said position removed from said casing, said casing being an elongated envelope with said inlet opening disposed at its rear end and its outlet opening disposed at its front end, said pivot means being disposed slightly forward of the center of gravity of said casing and apparatus incorporated in it for disposing said center of gravity over a central portion of said lever element to balance

said dryer over said lever element in both of its operative positions, a portion of said lever element extending a distance in front of said pivot means for preventing said casing from being tipped forward when it is supported upon a surface, a fin extending from the lower portion of said casing, said pivot means extending through said fin, said lever element including a front longitudinal groove within which said fin is inserted, and said grooved portion of said lever element incorporating a wall which engages the front of said fin to provide a stop for arresting said lever element in said position removed from said casing.

5. A structure as set forth in claim 4 wherein a projection extends from a portion of said casing disposed adjacent said front extension of said pivot means which is engaged by said front extension when said lever element is rotated to said position removed from said casing to provide a stop for said handle.

6. A structure as set forth in claim 5 wherein a hollow longitudinal projection extends from the lower rear of said casing with an opening in its back end, an electrical conduit from said blower unit extends through said open back end, and the surface of said handle portion disposed adjacent said casing incorporating a rear groove having an open back end which receives said longitudinal projection when said lever element is disposed adjacent said casing to permit said conduit to pass through the back end of said handle element.

7. A structure as set forth in claim 6 wherein a T-shaped member is secured within said casing over said conduit disposed within said longitudinal projection, said conduit includes a pair of insulated wires, said T-shaped element including an elongated leg forming a roof over the hollow space within said longitudinal projection, a pair of arms extending laterally from the front end of said T-shaped element for anchoring it within said casing, and connecting channels from under said leg and arms for diverting each of the pair of wires in said conduit in opposite directions under said arms.

8. A structure as set forth in claim 1 wherein said lever element includes a foot extending in front of said pivot means for preventing the forward tipping of said casing when it is resting upon a surface.

9. A structure for a portable hair dryer comprising a casing, blower and heating units mounted within said casing for propelling a stream of heated air from it, inlet and outlet openings in said casing for introducing air into and discharging it from said casing, a lever element, pivot means rotatably attaching said lever element to said casing for supporting it in its operative positions, said lever element being rotatable to positions adjacent and removed from said casing, the side of said lever element being laterally extended to provide a base for supporting said

dryer upon a surface when said lever element is in said position adjacent said casing, an end of said lever being relatively elongated and compact in cross section whereby it is constructed and arranged as a handle to permit said dryer to be held in the hand when said lever element is in said position removed from said casing, said casing being an elongated envelope with said inlet opening disposed at its rear end and its outlet opening disposed at its front end, said pivot means being disposed slightly forward of the center of gravity of said casing and apparatus incorporated in it for disposing said center of gravity over a central portion of said lever element to balance said dryer over said lever element in both of its operative positions, the front outlet end of said casing being shaped to provide an expanding bellmouth, coupling elements being disposed within a narrow portion of said bellmouth, a hose assembly being provided for conducting air from said front end of said casing, a coupling adapter at the end of said hose assembly for engaging said coupling elements in the front of said casing, said coupling adapter being engaged with said coupling elements for connecting said hose assembly to said casing, and apertures in said coupling adapter disposed adjacent a wider portion of said bellmouth when said hose is connected to said casing for providing a safety outlet for air should the other end of said hose become obstructed.

10. A structure as set forth in claim 9 wherein said hose assembly comprises a resilient helical wire covered by a flexible skin, said coupling adapter is a substantially rigid tubular element having an outside diameter which fits snugly within said helical wire, a helical ridge similar to the helical form of said wire disposed upon the outside of said tubular element for engaging said wire when said tubular element is screwed within said hose assembly to securely fasten said adapter to said end of said hose assembly in a manner which prevents said adapter from being unscrewed from said hose assembly after it is once screwed into it.
